UNITED STATES PATENT OFFICE.

NELSON W. TWISS, OF NEW HAVEN, CONNECTICUT.

AUTOMATIC CUT-OFF.

SPECIFICATION forming part of Letters Patent No. 247,588, dated September 27, 1881.

Application filed July 28, 1881. (No model.)

To all whom it may concern:

Be it known that I, NELSON W. TWISS, of the city of New Haven, State of Connecticut, have invented a new and useful Improvement 5 in Automatic Cut-Offs for Steam-Engines, of which the following is a full, true, and exact description, reference being had to the accompanying drawings.

On the 11th day of February, 1879, Letters 10 Patent of the United States, No. 212,285, were granted to me for improvement in cut-off gearing.

My present invention relates to an improvement upon said apparatus so patented to me. 15 I refer to that patent for a full description, the improvement only being shown in the present application. In that patent the steam was admitted and exhausted from the steam-cylinder by a steam-valve having a cylindrical face and 20 suitable ports, and the steam was cut off by an interior trip cut-off valve having likewise a cylindrical face traveling upon the inside of the steam-valve. This valve was tripped at a suitable position by a cam and closed by means 25 of a spring. In order that such valve should close rapidly a spring of considerable tension was requisite, and it was found that a considerable resulting jar occurred. I have therefore devised a traveling dash-pot moving with 30 the main valve and adapted to arrest the movement of the trip cut-off valve.

My drawing represents a vertical elevation on the side of the apparatus, showing the movable dash-pot.

35 L represents the arm controlling the cut-off valve, which valve is movable independently of the main valve. The main valve is operated, as before, by the link F². The arm B moves with the main valve, and upon it is supported the dash-pot D. Pivoted to the arm 40 operating the cut-off valve, at the point A, is the rod C, connected with the moving part of the dash-pot D. As soon as the hook P is

tripped, as described in the previous patent, the spring L' tends to throw the arm L to the 45 left, and the motion of this arm is arrested by the dash-pot D. This dash-pot, being supported upon the main valve and moved with it, is always in the proper position to arrest the movement of the cut-off valve.

50 It will be seen that my invention may also be applied to flat slide-valves having an independent cut-off valve sliding upon them; but it is particularly applicable to double rotary valves, as shown.

55 It is obvious that the location of the dash-pot may be greatly altered.

What I claim as my invention, and desire to secure by Letters Patent, is—

1. The combination, with a main steam-valve, of an independent cut off valve and a movable dash-pot carried by the main valve and adapted to arrest the movement of the cut-off valve at any point at which it may be tripped, substantially as described. 60

65 2. The combination of a rotary steam-valve, a rotary cut-off valve for cutting off on the back of the steam-valve, and a dash-pot partaking of the motion of the steam-valve and adapted to arrest the movement of the cut-off valve at any point at which it may be tripped, substantially as described. 70

75 3. The combination of a rotary steam-valve, a rotary cut-off valve cutting off on the back of said rotary steam-valve, an adjustable trip adapted to trip the cut-off valve at different points of the stroke, and a dash-pot partaking of the movement of the steam - valve and adapted to arrest the movement of the cut-off valve at its point of trip, substantially as de- 80 scribed.

NELSON W. TWISS.
